EXPANDING BRAKE OPERATOR

Pierre Farkas, Paris, France

Application May 27, 1946, Serial No. 672,516
In France November 18, 1942Section 1, Public Law 690, August 8, 1946
Patent expires November 18, 1962

5 Claims. (Cl. 188—78)

1

The present invention relates to an improved brake of the drum and expanding shoe type, whether mechanically, hydraulically or pneumatically operated.

A known form of vehicle brake comprises a pair of arcuate shoes pivotally anchored, at one pair of adjacent ends, on a fixed back plate and resiliently biased at their other ends against some form of expander which, when operated either mechanically, hydraulically or pneumatically, serves to pivot the two shoes outwardly against a brake drum. Instead of anchoring one pair of ends, it is known to articulate these ends together by a turnbuckle or other adjustable means for separating the shoes at this point so as to compensate for wear of the brake linings.

One arrangement for expanding the shoes includes a toggle joint consisting of a bell-crank lever articulated to one of the shoes and acting through a link on the other shoe, but in this proposed device both the link and the lever exert their action on the shoes along lines perpendicular to the axis of symmetry of the brake at points relatively far apart on the shoes and the device includes anchorages for the shoes which cause a see-saw action of the latter and hinder their smooth operation.

Having in mind the defects of the prior art brakes it is the object of the present invention to provide improved means for producing smooth and equal braking effects on the two shoes.

With these objects in view, and in accordance with the present invention, there is provided a wheel-brake including a brake-drum movable with the wheel, a relatively fixed back-plate, primary and secondary brake shoes articulated together at one pair of adjacent ends so as to be expandible against the drum, toggle mechanism mounted on the back-plate for expanding the other pair of adjacent ends of the shoes and comprising a link acting obliquely on the end of the primary shoe and a bell-crank lever exerting on the secondary shoe both a rearward push and a disengaging movement, and means for expanding the toggle mechanism.

In such a brake a wear-compensating device is preferably located on the back-plate at a position diametrically opposite the expander, and when the brake is operated, the primary jaw, that is to say, the jaw on the forward side of the expander in the direction of rotation, is first brought into contact with the drum whereupon the rotation is effective to wrap this jaw on the drum and to transmit its motion to that end of the secondary jaw opposite the expander, as a

function of the friction on the primary jaw, which then also wraps on to the drum. The toggle mechanism is preferably fully floating and may be mechanically, hydraulically or pneumatically operated.

The rearward and disengaging action of the bell-crank lever on the end of the secondary shoe reduces the pressure of this end of the secondary shoe against the drum and against a fixed abutment located between the ends of the shoes, so that there is produced a differential effect tending to equalize the circumferential action of the two shoes against the drum. Each shoe may be of a plurality of arcuate segments articulated together and touching with point contact only so as to facilitate their conforming to the surface of the drum.

The novel features that are considered characteristic of the invention are set forth with particularity in the appended claims. The invention itself, however, both as to its organization, and its method of operation, together with additional objects and advantages thereof, will best be understood from the following description of specific embodiments, when read in connection with the accompanying drawings, wherein like reference characters indicate like parts throughout and in which:

Figure 1 is a side view in elevation, partly in section of a mechanically operated brake,

Figure 2 is a cross-sectional view taken on the line II—II of Figure 1,

Figure 3 is a side view in elevation, similar to that of Figure 1, of a hydraulically operated brake;

Figure 4 is a cross-sectional view taken on the line IV—IV of Figure 3,

Figures 5 and 6 are fragmentary cross-sectional views taken longitudinally and transversely, respectively, of a hydraulic cylinder such as may be used in the system of Figures 3 and 4, and

Figures 7 and 8 are fragmentary cross-sectional views taken longitudinally and transversely respectively, of a modified form of hydraulic cylinder.

The brake illustrated in Figures 1 and 2 comprises a back plate 20 rigidly secured to a vehicle, a brake-drum 21 fixed to a road wheel of the vehicle, and mounted on the back-plate 20, a pair of arcuate brake-shoes 22 and 23, a device 24 for adjusting the shoes relative to each other to compensate for wear of the linings of the shoes and on which the shoes are pivoted; a wedge-shaped abutment 25, having radial faces, against which one pair of adjacent ends of the shoes may

bear, and a bracket 26 serving to hold and locate a sheathed brake-operating cable 27 ending in a bifurcated hook 28 engaging a shoe-expanding toggle mechanism.

The toggle mechanism includes a double bell-crank lever 29 connected with the shoe 23 and a double link 30 connected with the shoe 22. The two parts of the parallel pair of links 30 and 30', best shown in Figure 2, are kept in suitably spaced disposition by a washer 31 mounted on a pin 32 fixed on the back-plate 20. The bifurcated hook 28 is biased to its upper-most position by a helical spring 33 compressed between a collar 34 on the hook and the bracket 26. The double link 30 is pivotally connected to the shoe 22 by a pivot 35 and the shorter arm of the double bell-crank lever 29 is pivotally connected to the other shoe 23 by a pivot 36, the lever and link being pivotally connected together by a pivot 37 to constitute the knuckle of the toggle joint which is operated upon movement of the longer arm of the bell-crank lever by the hook 28 which is operated by the cable 27. It should be noted that the three points of articulation 35, 36 and 37 are fully floating and that the link 30 is oblique to the axis of symmetry II-II of the brake.

The top adjacent ends of the shoes 22 and 23 are biased against the segmental abutment 25 by a pair of helical springs 38 and 39. The shoes are, preferably, divided into segments which are adjustably connected at 40 and 41, so that they can pivot at these points. The shoes have their lower ends resiliently retained in pivotal contact with the wear-compensating device 24 by a spring 42. The wear-compensating device 24 is such as to permit any circumferential movement of the lower end of shoe 22 to be transferred to the shoe 23 and is preferably automatic in operation.

In the operation of the brake, when the brake-operating cable 27 is pulled the hook 28 is retracted in the direction of the arrow S. The bell-crank lever 29 swings about pivot 36 and pushes the link 30, in a direction oblique to the axis of symmetry, so as to force the upper end of the primary shoe 22 against the drum in the direction r. As the link 30 swings about pivot 35 in clockwise direction, the thrust of the shoe 22 against the drum approaches its extreme upper end. At the same time, the bell-crank lever 29, swinging about pivots 36 and 37 tends, simultaneously, to push the secondary shoe 23 in the direction u and to withdraw its upper end away from the drum in the direction t.

Assuming the drum to be rotating in the direction of arrow A, it will be seen that shoe 22 is immediately self-wrapping and that its slight anti-clockwise movement is transmitted, through the device 24, to force the shoe 23, at its lower end, against the drum whereupon the action of this shoe is also self-wrapping.

It is to be particularly noted that, although shoe 23 is also self-wrapping, starting from its lower end, its upper end is not jammed against the abutment 25 because the bell-crank lever 29 holds it away from the abutment. Self-wrapping action thus, as it were, commences at the upper end of shoe 22, and the several sections of the two shoes wrap themselves against the drum in anti-clockwise sequence right around the drum, up to the upper end of shoe 23.

The modified devices illustrated in Figures 3 to 8 operate upon the same principle as that of Figures 1 and 2, but the mechanical control is replaced by hydraulic control. Pivoted on the

shoe 22 by a pivot 43 is a piston 44 working in a cylinder 45, a seal between the piston and cylinder being provided by a cup washer 46 biased against the piston by a spring 47 under compression between the piston and cylinder, as best shown in Figures 5 and 7. Pivoted on the shoe 23 by a pivot 48 is a bell-crank lever 49 provided with a lug or spur 50 and having threaded through its lower end an adjustable screw 51, the end of which bears against the outer end of the cylinder, in a socket formed therein.

Fluid under pressure can be admitted and withdrawn from the cylinder 45, above the piston, by way of a pipe 52, as shown in Figures 5 and 7. A bleeder duct 53 leads to a bleeder hole closed by a plug 54 screwed to the outside of the housing 20 as shown in Figure 6, or inside the housing as shown in Fig. 8. The washers 55 and 56 and a spring 57 (Figure 4) locate the device laterally, but permit movement across the housing 20.

The hydraulic mechanism is operated upon actuation of the usual brake pedal or lever (not shown) which serves to force fluid under pressure through pipe 52 into the cylinder 45 thus urging the piston 44 towards shoe 22 and urging the cylinder 45 towards shoe 23. But, while the shoe 22 is moved towards the drum 21 in a direction oblique to the axis IV-IV, the effect of the spur 50 on the bell-crank lever is to cause the upper end of the shoe 23 to be moved approximately tangentially downwards. In other words, this end is moved, as it were, downwards and around the inside of the drum with a slight movement away from the drum.

Assuming the drum to be moving in the direction of the arrow A, the shoe 22 wraps on to the drum, from its upper end downwards, and is also moved slightly downwards. This anti-clockwise shift is transferred through the wear-compensating device 24 to the lower end of shoe 23 which thereupon wraps on to the drum from its lower end upwards. It will be noted that, as before, the bell-crank lever serves to hold the upper tip of shoe 23 away from the abutment 25.

The hydraulic piston and cylinder illustrated in Figures 7 and 8 are similar to that of Figures 5 and 6 except that the supply line 52 and the bleeder plug 54 are attached to the cylinder 45 in simpler fashion.

It will be appreciated that, in all of the devices described, the shoes exert pressure on practically the whole peripheral surface of the drum since the fixed abutment 25 can be made very small, and the equal smooth application and self-wrapping effect is rendered possible by virtue of the fact that the shoes have no anchorages at their upper ends.

Although a certain specific embodiment of the invention has been shown and described, it is obvious that many modifications thereof are possible. The invention, therefore, is not to be restricted except insofar as is necessitated by the prior art and by the spirit of the appended claims.

Having thus described my invention, what I claim and desire to secure by Letters Patent is:

1. A brake comprising a movable brake-drum, a relatively fixed back-plate, primary and secondary brake shoes articulated together at one pair of their adjacent ends so as to be expandable against the drum, toggle mechanism for expanding the other pair of adjacent ends of the shoes and mounted on the back-plate, said toggle mechanism including a link connected at one end di-

rectly to the end of the primary shoe to act obliquely outward thereon and pivotally connected at the other end to a bell crank lever which is pivotally connected directly to the secondary shoe to exert both a rearward push and a disengaging movement, and means for expanding the toggle mechanism.

2. A brake comprising a movable brake-drum, a relatively fixed back-plate, brake-operating means mounted on the back-plate, primary and secondary shoes articulated together at one pair of their adjacent ends so as to be expandible against the drum, said shoes each comprising a plurality of segments that are adjustably connected in end-to-end relation, a fixed abutment between the other pair of adjacent shoe-ends, spring means biasing said latter pair of adjacent shoe-ends respectively toward said abutment to retract and center said shoes, and toggle mechanism for expanding the shoe-ends adjacent the abutment and including a link and a bell-crank lever, said link being pivoted at one end on the primary shoe adjacent the abutment so as to be oblique to the axis of symmetry of the brake and upon actuation to exert an obliquely outward pressure on said shoe and its segments against said brake drum, said link being pivotally connected at the other end to the knuckle of the bell crank lever, said bell-crank lever having one arm pivoted directly to the secondary shoe adjacent the abutment and the other arm connected with the brake operating means, and guides floatingly mounted on the back plate for holding the toggle mechanism in correct lateral position of the back plate but permitting peripheral floating thereof.

3. A brake comprising a movable brake-drum, a relatively fixed back-plate, primary and secondary brake-shoes articulated together at one pair of adjacent ends so as to be expandible against the drum, a fixed abutment mounted on the back plate between the other pair of adjacent ends of the shoes, toggle mechanism for expanding the shoe-ends adjacent the abutment comprising a bell crank lever and a piston and cooperating cylinder, said bell crank lever having one arm pivoted on the secondary shoe and the other arm articulated to one end of the piston and cylinder, the other end of said piston and cooperating cylinder being articulated to the primary shoe adjacent the abutment and brake operating means for controlling the flow of fluid to and from the cylinder.

4. A wheel-brake including a movable brake drum, a relatively fixed back-plate, primary and secondary brake-shoes articulated together at one pair of adjacent ends so as to be expandible against the drum, a fixed abutment mounted on the back plate between the other pair of adjacent ends of the shoes, toggle mechanism for expanding the shoe-ends adjacent the abutment comprising a bell crank lever and a piston and cooperating cylinder, said bell crank lever having one arm pivoted on the secondary shoe and the other arm articulated to one end of the piston and cylinder, the other end of said piston and cooperating cylinder being articulated to the primary shoe adjacent the abutment and brake operating means for controlling the flow of fluid to and from the cylinder.

5. A brake as defined in claim 4, wherein the axis of the piston and cylinder is oblique to the axis of symmetry of the brake.
